UNITED STATES PATENT OFFICE.

HORACE F. NASON, OF NATICK, MASSACHUSETTS.

WAX-THREAD SEWING-MACHINE.

SPECIFICATION forming part of Letters Patent No. 256,156, dated April 11, 1882.

Application filed November 21, 1881. (No model.)

To all whom it may concern:

Be it known that I, HORACE F. NASON, of Natick, in the county of Middlesex and State of Massachusetts, have invented certain new and useful Improvements in Wax-Thread Sewing-Machines, of which the following, taken in connection with the accompanying drawings, is a specification.

My invention relates to certain improvements in the construction and arrangement of the working parts of wax-thread sewing-machines, whereby such machines are rendered capable of doing first-class general work at a much higher rate of speed than has been possible with the machines as heretofore constructed, and is an improvement in some respects upon and in others an adaptation of the machine designed by me for special work, and shown and described in Letters Patent No. 227,288, granted to me May 4, 1880, to doing general work, which improvements will be best understood by reference to the description of the drawings and to the claims to be hereinafter given.

Figure 1 is a side elevation of a machine embodying my invention. Fig. 2 is an elevation of the opposite side. Fig. 3 is an elevation of the front end. Fig. 4 is a vertical section on line $x-x$ on Fig. 1. Fig. 5 is a vertical section on line $y-y$ on Fig. 2, looking toward the front end of the machine. Fig. 6 is a vertical section through the wax-tank on line $z-z$ on Figs. 3 and 4. Figs. 7, 8, 9, 10, 11, 12, and 13 are details to be hereinafter referred to.

A is the frame of the machine, upon which are mounted all the working parts, said frame being provided with the upwardly-projecting post A', to the upper end of which is secured the work-supporting plate A², having formed in or near its center a suitable opening for the passage of the awl and needle, all in a well-known manner.

B is the driving-shaft, mounted in bearings in the frame A, near its base and below the work-supporting plate, and having secured upon its rear end the hand-wheel C and cone-pulley D, and upon its front end the crank-disk a, in the front face of which is set the crank-pin a', as shown in Fig. 10. The crank-disk a revolves within a recess, b, formed in the front face of the feed-bar E, near its lower end, as shown in Fig. 3. The recess b has a

vertical width just equal to the diameter of the disk a, and a horizontal length equal to the diameter of said disk plus the throw of the eccentric e, which is secured upon the shaft B just in the rear of the feed-bar, and revolves between two anti-friction rolls, c' and c², which are mounted upon studs set in the rear face of the feed-bar E, as shown in Fig. 9. The feed-bar E is pivoted to the front face of the post A' by the pin or stud d, which is adjustably secured in a slot, d', cut through said post, and carries at its front end the T-shaped block e, which fits into a correspondingly-shaped slot, e', formed in the rear side of the feed-bar, as shown in Figs. 2 and 9. The upper and lower walls of the recess b are formed by the hardened steel plates f f, secured in position, as shown.

The shaft B has also secured thereon the eccentric F, carrying the eccentric-rod F', the upper end of which is jointed to the short arm of the lever G, the opposite end of which is forked to receive the block g, mounted on the screw-pin g', set in the side of the awl-bar H, which has its bearings in the front end of the goose-neck or upper portion of the frame A, as shown.

I is the looper-bar, also mounted in the upper front portion of the frame A, and having secured thereon the cylinder-cam I', in the path h of which works the roll h', mounted upon a stud set in the back side of the lever G, as a means of imparting to said bar and its looper i the necessary intermittent vibratory motion about the axis of said bar, said cylinder-cam and its connection with the lever G being best shown in Figs. 11 and 13.

J is the presser-foot, slotted to permit the passage of the needle and awl and firmly secured to the lower end of the bar J', which has its bearings in the upper front portion of the frame A, and has secured thereto, between its bearings, the collar J², from the front side of which projects the arm j, which enters the slot j' formed in the cap A³ on the upper front portion of the frame A, and serves to prevent the presser-foot bar from being rotated in its bearings.

The collar J² is secured in position on the bar J' by the long screw-stud j², which also serves as a bearing for the front or movable end of the

spring K, the tension of which serves to press the foot J hard upon the work to be sewed.

The presser-foot J is lifted, when desired, by means of the rocker-shaft L, carrying at its front end the lifter-toe L', the movable end of which engages with the under side of the collar J², and at its rear end the arm L², which, when the machine is in working condition, is connected to a treadle, (not shown,) by means 10 of which said shaft L may be partially rotated about its axis in an obvious manner.

M is the needle-bar, mounted in a bearing formed in the feed-bar E, and having secured in its upper end the barbed needle k, as shown.

15 A reciprocating motion is imparted to the needle-bar M by means of the crank-pin a' and the connecting-rod N, the lower end of which embraces said crank-pin, and the upper end in like manner embraces the pin l, set in the front 20 side of the needle-bar and adapted to move up and down in the slot l' formed in the feed-bar E, as shown in Fig. 3.

O is the cast-off bar, having its bearing in the feed-bar E in close proximity to and parallel with the needle-bar M, and carrying in its upper end the cast-off m, secured thereto, as described in my previous patent before cited. The bar O has secured thereto the pin n, which projects at right angles thereto through the 30 slot n' formed in the feed-bar E and some little distance beyond the front face of said feed-bar and within the slot o formed in a sidewise extension of the connecting-rod N, as shown in Figs. 3 and 10. The slot o formed in the 35 connecting-rod N has fitted to each end thereof a filling-block, o', arranged to be adjusted toward or from each other, to increase or diminish the length of the slot and regulate the time of operating the cast-off by means of the screws p p, constructed as shown in Fig. 12, and secured in the rod N, so as to revolve freely without endwise movement therein, by pins which pass through said rod in a position to engage with the circumferential grooves p' p' formed 40 in said screws, as shown.

45 The looper i is materially improved in form, as compared with the loopers heretofore generally in use, for the purpose of raising the larger portion of it higher above the plane in 50 which the thread is carried around the needle than heretofore, so that the operator may more readily see the operation of the sewing as it progresses and detect any imperfection therein. Prior to my invention such loopers have

55 been made with the main body of the looper horizontal, or nearly so, and in the same horizontal plane as the end containing the eye for the thread, which I have found to be very objectionable in doing some kinds of work, and 60 to obviate this objection I make my looper of the form shown in Figs. 7 and 8, with the bend to one side from the vertical shank which enters the looper-bar, as shown at q, at a point some distance above the level of the plane in 65 which the thread is carried around the needle, and extending it obliquely downward in a

straight, or nearly straight, line, as viewed in elevation, to a point within about an eighth of an inch (more or less) of its end, as at q', and then giving it a sudden bend downward, as 70 shown in Fig. 8, the eye for the thread passing through said downwardly-bent or lower vertical portion.

P is the wax-tank, having a cylindrical interior chamber, a filling-orifice closed by the screw-plug P', the nose P², and mounted upon the stud r set in the frame A. The nose P² is chambered or counterbored out to receive the rubber tube s and the screw-tube s', and by the revolution of the latter the former is compressed or allowed to 80 expand lengthwise to regulate the friction upon the thread, which passes through said rubber and screw-tubes after being waxed in a well-known manner. The thread enters the wax-tank through the orifice t, the entrance to which 85 is in the upper end of the annular lip surrounding the filling-orifice, and between the end of said lip and the flange of the screw-plug P', so that the thread may have a slight pressure applied to it by screwing down the plug P' 90 upon the rubber packing-ring t' to a greater or less extent, according to the friction desired. The plug P' also serves the purpose of excluding dust and dirt from the wax-tank, thus 95 keeping the wax in better condition than when the tank is open to the atmosphere, as heretofore practiced.

The presser-foot bar J' has secured thereon the block R, having formed upon one side thereof a series of ratchet-teeth, as shown in Fig. 4. 100

The awl-bar H has pivoted thereto the pawl w', with its movable end upward, and in position to engage with the teeth on the block R during the latter part of the upward movement of said awl-bar, and thus lift the presser-foot from the work to permit the work to be fed by the vibration of the feed-bar and the needle-bar carried thereby. The time of engagement of the pawl w' with the teeth on the block R is determined and regulated by the 110 shield-plate w, adjustably secured to the rear side of the cap A³, and projecting therefrom toward the rear of the machine, between the awl-bar and presser-bar, as shown in Figs. 2 and 4.

115 The cast-off bar O is held stationary at each extreme of its movement till power is applied thereto to move it by the spring-actuated friction-pins w w', substantially as described in my prior patent before cited.

120 What I claim as new, and desire to secure by Letters Patent of the United States, is—

1. The combination, in a wax-thread sewing-machine, of the fixed post A', carrying the work-supporting plate A², the driving-shaft B, carrying the disk a and eccentric c, and the feed-bar E, provided with the recess b and rolls c' and c², and adjustably pivoted at or near the middle of its length to said post A', and carrying the needle-bar M and cast-off bar O, all 125 arranged and adapted to operate substantially as described.

2. The combination of the feed-bar E, pivoted at or near the middle of its length to the post A', and provided with the recess b and the rolls c' and c², the shaft B, the crank a a', the eccentric e, the needle-bar M, the connecting-rod N, provided with the slot o, the blocks o' o', fitted within the slot o and adjustable therein by the screws p p, and the cast-off bar O, provided with the pin n, all arranged and adapted to operate substantially as and for the purposes described.

3. The looper i, having its main portion inclined obliquely downward, as from q to q', and its extreme lower portion bent to a perpendic-

ular, or nearly perpendicular, position, substantially as and for the purposes described.

4. The wax-tank P, provided with the covering-plug P', the orifice t for the entrance of the thread, the nose P², the rubber tube s, and the screw-tube s', all arranged, combined, and adapted to operate substantially as described.

Executed at Boston, Massachusetts, this 19th day of November, A. D. 1881.
